Inventor

John Cornelius O'Brien

By *J. C. O'Brien*, Atty.

UNITED STATES PATENT OFFICE.

JOHN CORNELIUS O'BRIEN, OF ST. LOUIS, MISSOURI.

DESIGN FOR A WATCH-CHAIN.

Specification for Design.

Patented Feb. 22, 1921.

57,146.

Application filed November 21, 1918. Serial No. 263,631. Term of patent 14 years.

To all whom it may concern:

Be it known that I, JOHN CORNELIUS O'BRIEN, a citizen of the United States, residing at St. Louis, Missouri, have invented a new, original, and ornamental Design for Watch-Chains, of which the following is a specification, reference being had to the accompanying drawing, forming a part thereof.

The figure is a front elevational view of

my new, original and ornamental watch chain.

I claim:

The ornamental design for a watch chain, as shown.

JOHN CORNELIUS O'BRIEN.

Witnesses:

M. P. SMITH,
M. A. HANDEL.
